(57) **CLAIM**

The ornamental design for a bus bar for wind turbine, as shown and described.

DESCRIPTION

FIG. 1 is a perspective view of a bus bar for wind turbine, showing our design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The bus bar for wind turbine is shown with a symbolic break in its length and height as illustrated with the dash-dot broken lines. The appearance of any portion of the bus bar for wind turbine between the break lines forms no part of the claimed design. In the drawings, the evenly spaced broken lines illustrate portions of the bus bar for wind turbine which form no part of the claimed design.
